UNITED STATES PATENT OFFICE.

SOREN ROBERTSON, OF CLEVELAND, OHIO.

CAR-AXLE BOX.

SPECIFICATION forming part of Letters Patent No. 487,231, dated November 29, 1892.

Application filed March 4, 1892. Serial No. 423,733. ((No model.)

To all whom it may concern:

Be it known that I, SOREN ROBERTSON, of Cleveland, in the county of Cuyahoga and State of Ohio, have invented certain new and useful Improvements in Journal-Boxes and Attachments; and I do hereby declare the following to be a full, clear, and exact description of the invention, such as will enable others skilled in the art to which it pertains to make and use the same.

My invention relates to improvements in car-axle or journal boxes and attachments; and my invention consists, among other things, in a peculiar arrangement of journal-packing for lubricating the journal of the axle and mechanism for supporting this packing relative to the journal, whereby the packing does not require frequent renewing and whereby the journal receives better lubrication.

My invention consists, also, in means for more effectually excluding dust and dirt from the journal-box and journal and more effectually preventing the escape and consequent waste of oil than was possible by the means heretofore devised.

My invention consists, further, in a collar revolvable with the wheels and car-axle, but connected with the journal-box in such a manner that it offers resistance to the endwise thrust of the axle and wheels without liability of injuriously straining any of the parts of the box and that it can be removed endwise off the axle with the journal-box.

My invention consists, moreover, in a plate bolted to the top of the journal-box and provided with a perforated boss at one side of the top of the box, whereby the steady-pin depending from and rigidly connected with the car-body and adapted to be received by the perforation of said boss may extend through and below said boss—that is, said perforated boss will accommodate, without interference from or with the journal-box, the up-and-down movement of the steady-pin resulting from the lurching and swaying of the car-body.

My invention consists, also, in providing the casing of the journal-box at either side and at the lower end thereof, with a laterally-projecting lug or flange, with the lower surface of such lugs or flanges preferably flush

with the bottom of the box, and in providing the journal-box at or near the forward end thereof with a bracket or depending member, 55 said laterally-projecting lugs or flanges and depending member being preferably perforated for the passage of bolts securing the side piece of the car-truck to the journal-box, thus effectually supporting and steadyng the 60 car-truck.

My invention consists, also, in certain features of construction and in combination of parts hereinafter described, and pointed out in the claims.

In the accompanying drawings, Figure 1 is a side elevation in central vertical section of a journal-box embodying my invention. Fig. 2 is a horizontal section on line 2 2, Fig. 1. Fig. 3 is a front end elevation in section on line 3 3, Fig. 1. Fig. 4 is a plan of the box. Fig. 5 is a perspective of the oil-feeding device.

A represents the casing of my improved journal-box, A' the oil-chamber, and A² the lid or cover of the box. B represents the 75 journal-bearing; C, the journal of the axle; C', the hub of the wheel, and D the sliding stop plate or end bearing of the axle. A³ represents the rear wall of the oil-chamber of the box that is perforated, as at A⁴, for the 80 passage of the journal of the axle.

E represents the journal-packing or lubricant-vehicle that is located within the oil-chamber below the journal of the axle. This packing comprises a comparatively-thick 85 sheet of felt or other material suitable for the purpose bent approximately to the form of an inverted U, as shown in Fig. 5, two blocks or plates F and G being provided, respectively, at the top and bottom of and within the U. 90 The packing is secured to the lower block G in any suitable manner, preferably as shown, by strips H, of leather or other suitable material, tacked or nailed to said block or plate. Blocks or plates F and G are recessed on opposing surfaces relative to each other, as at f g, and I represents springs, preferably coil-springs, as shown, that are seated within said recesses. Block or plate F at either end is preferably flush with the edge of packing E; but 100 block or plate G extends, preferably, beyond either end of the U-shaped sheet of packing, being of such length as to nicely but easily fit within the oil-chamber A' and rest upon

the bottom of the latter. End g' of block or plate G , that extends forward of the packing, thus serves as a handle.

The device, composed of the journal-packing or lubricant-vehicle E , plates or blocks F G , with intermediate springs I , shall herein-after be referred to in this specification as the "oil-feeding" device.

The oil-feeding device, as aforesaid, extends approximately the entire length of the oil-chamber and the location of the top or central portion of the packing or lubricant-vehicle of the oil-feeding device relative to the journal of the axle is such that the latter will engage the packing, as shown more clearly in Fig. 3, and somewhat depress the top or central portion of the packing, as at e , and bulge it out laterally, as at e' , against the side walls of the oil-chamber, upper plate or block F and springs I constituting a cushion that acts in the direction to hold the journal-packing or lubricant-vehicle in contact with the journal. It will thus be observed that the packing or lubricant-vehicle of the oil-feeding device presents a large surface to the journal of the axle, thereby affording better lubrication, and the packing being preferably thick at the top of the oil-feeding device (at least not diminished in thickness) it follows that said packing will last a long time, and when this top portion has been worn away the journal will still be lubricated by the packing at the sides of the oil-feeding device. At the rear of the oil-chamber the casing of the journal-box is enlarged laterally and upwardly, as at a .

L represents an annular wearing plate or disk, of comparatively-hard fibrous material, preferably wood fiber, the same being located within the chamber of the enlarged portion a of the box immediately at the rear of the back wall of the oil-chamber, the centrally-located opening of plate or disk L being just sufficiently large to permit the passage of the journal of the axle.

Immediately at the rear of annular plate or disk L is located a collar M , the forward end of which is annularly flanged externally, as at M' , such flanged portion of collar M being preferably of the same size diametrically as plate or disk L .

Immediately at the rear of annular flange M' of collar M the casing of the enlarged portion a of the journal-box has an inwardly-extending flange all round the box, as at a' , the same being circular at its inner end, leaving a central opening sufficiently large relative to the external periphery of flange M' of collar M as to easily permit the removal of the collar from the journal-box when required and its insertion. Chamber a^2 , thus formed between enlarged portion a of the casing of the box and annular flange M' of collar M and between the internal flange a' and forward wall of the enlarged portion of the box, is filled with suitable packing K , preferably felt.

Collar M' extends rearward of the journal-box and at the rear end has an outwardly

and rearwardly projecting lug or member M^2 , that is adapted to fit within a corresponding recess C^2 in hub C' of the car-wheel, so that when the box is in position with collar M' mounted upon the axle by means of rearwardly-projecting member M^2 of the collar and recess C^2 of the hub of the car-wheel collar M' will be locked to the hub of the wheel and caused to revolve with the wheel and axle.

Collar M' is held against wearing disk or plate L by a plate Q , preferably of cast-iron, that fits outside collar M' within the rear end of the enlarged portion a of the casing of the journal-box and is secured to the forward wall of said enlarged portion of the casing by means of screws or bolts R , a gasket S being interposed, however, between plate Q and the opposing surfaces of flanges a' and M' of the casing of the box and collar M , respectively, gasket S being of course of such thickness within the chamber between flange a' of the casing of the box and collar M as to fill said chamber, so that when plate Q is secured in place gasket S will fit snugly against flange M' of collar M and hold collar M against wearing disk or plate L . Plate Q has of course a slot Q' in open relation with the central opening of the plate, slot Q' being of such shape and size relative to the outwardly and rearwardly projecting lug or member M^2 of collar M as to readily permit the removal and assemblage of said plate. Collar M' has also an internal annular groove, as at M^3 , filled with packing T , preferably leather.

By the construction hereinbefore described, with the parts properly made and assembled, it will readily be observed that there is not the least possible opportunity for dust and dirt to obtain ingress at the rear end of the journal-box to the journal of the axle and oil-chamber of the box or for the escape and consequent waste of oil from the box.

Collar M is removable endwise from the axle with the journal-box—in fact, is an attachment of the box—and the journal-box and attached collar M having been removed from the axle the parts can readily be separated for inspection, repairs, &c.

Plate Q , flange a' , and the forward wall of chamber a^2 of the enlarged portion a of the casing of the box are of course provided with suitable holes for the reception of screws or bolts R , that, as aforesaid, secure plate Q in place to hold the respective parts properly assembled.

The journal-box at the bottom of chamber a^2 is slotted for the reception of a slide N , the latter extending, preferably, the entire width of said chamber and adapted to snugly fit therein, but not so snugly as to prevent the slide from being easily moved in and out. The box at the top of chamber a^2 is perforated for the passage of bolts O , a bolt being provided at either side of and passing through chamber a^2 , and the screw-threaded end of the bolts passing through a correspond-

ingly-threaded perforation in slide N. In case of any leakage of the box, such leakage will likely be first perceptible at the lower portion of chamber a^2 . Hence the provision of 5 slide N aforesaid, whereby, for instance, from carelessness on the part of the workmen, the packing in chamber a^2 should not have been sufficiently compressed and the box should consequently leak. By manipulating bolts 10 O slide N can be advanced to compress the packing against the peripheral surface of wearing plate or disk L and flange M' of collar M and stop the leakage without necessitating the separation of the respective parts 15 of the box; also, if access to chamber a^2 were necessary, for instance, for renewing the packing in said chamber by means of slide N such access is readily had without necessitating the disturbance of any other part of 20 the box.

To the top of the journal-box is bolted a plate U, the same preferably being made to fit nicely between the enlarged portion a of the box and a ridge A^5 at the forward end of 25 the top of the box, plate U having a recess U' on its under side, adapted to fit a corresponding projection A^6 at the central portion of the top of the box, the plate and box being perforated at this point for the passage of a bolt 30 W for securing said plate to the box, the top wall of the chamber of the box being provided with a recess for receiving the head of the bolt flush therewith. Plate U at one side of the journal-box terminates in a boss U^2 , that 35 is vertically perforated, as at U^3 , for the reception of the steady-pin (not shown) depending from and rigidly connected with the car-body. By this provision, that is of no inconsiderable 40 importance, the steady-pin referred to can extend through the boss and have entire freedom to move up and down with the lurching or swaying of the car-body without impediment by or interference with the journal-box.

As shown in Figs. 2 and 3, the journal-box 45 at either side and at the lower end thereof has a laterally-projecting lug or flange A^7 , preferably flush with the bottom of the box, and forward of these lugs or flanges has a depending bracket or member A^8 , said laterally-projecting lug or flanges and depending bracket or member being perforated, as at 50 a^7 a^8 , respectively, for the reception of bolts for securing the side piece of the car-truck to the bottom of the journal-box at the rear of 55 depending bracket or member A^8 of the box, thus effectually supporting and steadyng the car-truck.

What I claim is—

1. In a journal-box of the variety indicated, 60 an oil-feeding device located in the oil-chamber of the box and comprising a packing or lubricant-vehicle adapted to be engaged by the journal and secured to a plate or block adapted to rest upon the bottom of the oil-chamber, and a cushion interposed between 65 said plate or block and the top or central portion of the packing or lubricant-vehicle and

adapted to hold the latter in contact with the journal, substantially as set forth.

2. In a journal-box of the variety indicated, 70 an oil-feeding device located in the oil-chamber of the box and comprising a packing or lubricant-vehicle adapted to be engaged by the journal, a plate or block to which the packing or lubricant vehicle is secured, said 75 plate or block being adapted to rest upon the bottom of the oil-chamber and terminating at the forward end in a handle, and a cushion interposed between the said plate or block and the top or central portion of the packing 80 and adapted to hold the latter in contact with the journal, substantially as set forth.

3. In a journal-box of the variety indicated, 85 an oil-feeding device located in the oil-chamber of the box, said oil-feeding device comprising a sheet of packing bent approximately to the form of an inverted U in cross-section, the top or central portion of the packing being adapted to be engaged and depressed by the journal and bulged out laterally, substantially as indicated, the sheet of packing 90 at its longitudinal ends being secured to a plate or block adapted to rest upon the bottom of the oil-chamber, and a cushion interposed between said plate or block and the top or central portion of the packing and 95 adapted to hold said packing in contact with the journal, substantially as set forth.

4. In a journal-box of the variety indicated, 100 an oil-feeding device located in the oil-chamber of the box, said oil-feeding device comprising a sheet of packing bent approximately to the form of an inverted U in cross-section, the top or central portion of the packing being adapted to be engaged and depressed by the journal and bulged out laterally, substantially as indicated, the sheet of packing 105 and its longitudinal ends being secured to a plate or block, as at G, adapted to rest upon the bottom of the oil-chamber, a plate or block, as at F, located above the aforesaid plate or block G and below the top or central portion of the sheet of packing, and one or more springs, as at I, interposed between plates or blocks F G and acting in the direction to hold the 110 packing in contact with the journal, substantially as set forth.

5. In a journal-box of the variety indicated, 115 a collar removably attached to and extending rearwardly of the box, said collar being adapted to be mounted upon the journal with the box and connected to the journal, whereby to revolve with the journal, substantially as set forth.

6. In a journal-box of the variety indicated, 120 a collar removably connected with and extending rearwardly of the box, said collar being adapted to be mounted upon the journal with the box and having a rearwardly-projecting lug or member, substantially as and 125 for the purpose set forth.

7. In a journal-box of the variety indicated, 130 a collar removably connected with and extending rearwardly of the box, said collar be-

ing adapted to be mounted upon the journal with the box and revolve with the journal and having an internal annular groove filled or adapted to be filled with packing, substantially as and for the purpose set forth.

8. In a journal-box of the variety indicated, the casing whereof is enlarged rearward of the oil-chamber, a collar removably connected with said enlarged portion of the box and adapted to be mounted upon and connected with the journal and revolve with the journal, a wearing disk or plate between the forward end of said collar and the adjacent wall of the enlarged portion of the casing of the box, and suitable means for holding the collar against said wearing plate or disk, substantially as set forth.

9. In a journal-box of the variety indicated, a collar removably connected with the box rearward of the oil-chamber, a chamber in the box surrounding said collar and supplied or adapted to be supplied with packing, said collar being adapted to be mounted upon the journal with the box and revolve with the journal, and suitable means for holding said collar from moving endwise, substantially as set forth.

10. In a journal-box of the variety indicated, a chamber located in the rear portion of the box and supplied or adapted to be supplied with packing to exclude dust and dirt and prevent the escape of oil from the box, a slide located in the lower portion of said chamber, the bottom of the casing of the box being slotted or perforated for the insertion and removal of said slide, and suitable means for manipulating said slide to more or less compress the packing within the chamber aforesaid, substantially as set forth.

11. In a journal-box of the variety indicated, the casing whereof is enlarged rearward of the oil-chamber, a collar removably connected with the enlarged portion of the box and adapted to revolve with the journal, said collar having a lateral annular flange at its forward end, a wearing disk or plate interposed between the forward end of said collar and the adjacent wall of the enlarged portion of the casing of the box, a plate adapted to close the rear end of the box about the collar and rigidly but removably secured to the box, and a gasket interposed between said rigid plate and the lateral annular flange of the collar aforesaid, said rigid plate and gasket being adapted to hold the collar against the wearing plate or disk forward of the collar, substantially as set forth.

12. In a journal-box of the variety indi-

cated, the casing whereof is enlarged rearward of the oil-chamber, a collar removably connected with the enlarged portion of the box and adapted to revolve with the journal, said collar having a lateral annular flange at its forward end, a wearing disk or plate interposed between the forward end of said collar and the adjacent wall of the enlarged portion of the casing of the box, the casing of the box having an inwardly-projecting flange located at the rear and outside of said annular flange on the collar, the chamber thus formed between said annular flange of the collar and the surrounding walls of the casing of the box being supplied or adapted to be supplied with packing, a plate adapted to close the rear end of the box about the collar and rigidly but removably secured to the box, and a gasket interposed between said rigid plate and opposing surfaces of the aforesaid flanges of the casing of the box, said rigid plate and gasket being adapted to hold the collar against the wearing plate or disk forward of the collar, substantially as set forth.

13. In a journal-box of the variety indicated, a plate removably secured to the top of the box, said plate at one side of the box being provided with a boss vertically perforated, substantially as and for the purpose set forth.

14. In a journal-box of the variety indicated, a plate bolted to the top of the box, the top of the main chamber of the box being recessed for receiving the head of the bolt flush therewith, said plate at one side of the box being provided with a boss vertically perforated, substantially as and for the purpose set forth.

15. In a journal-box of the variety indicated, a plate removably secured to the top of the box, the casing of the box being enlarged, as at a , and having a ridge at the forward portion of the top thereof, as at A^5 , and having an upwardly-projecting lug, as at A^6 , between parts a and A^5 and adapted to enter a corresponding recess in the under side of the plate aforesaid, said plate at one side of the box being provided with a boss vertically perforated, substantially as and for the purpose set forth.

In testimony whereof I sign this specification, in the presence of two witnesses, this 15th day of January, 1892.

SOREN ROBERTSON.
